TUMBLING MILL

Edward W. Benson, Romulus, Mich.

Application September 1, 1931. Serial No. 560,604

3 Claims. (Cl. 51—164)

This invention relates to tumbling mills and the object of the invention is to provide a tumbling mill in which the castings are secured in position in the mill and are rotated about a common axis while being cleaned.

Heretofore it has been the practice in tumbling mills to place the castings in the mill and tumble the castings about with the tumbling jacks until they are clean but this method results in a considerable loss of otherwise perfect castings due to the fact that the castings in tumbling together become cracked or broken or important lugs or flanges are knocked off.

With my tumbling mill the castings are each secured firmly to a central support and are rotated about a common axis while the jacks are free to move about, between, and through the castings to clean the castings and at the same time, there is no opportunity for loss by breakage due to the castings tumbling and bumping together.

One of the objects of my invention is to provide a simple and efficient means for locking the castings in place in the mill whereby they are held in position during rotation.

Another object of the invention is to provide an arrangement whereby a tension may be placed on the locking means from the exterior of the mill.

A further object of the invention is to provide a tumbling mill in which the castings may be turned about within the housing without moving the housing and in which the housing may be locked to rotate with the castings.

These objects and the several novel features of the invention are hereinafter more fully described and claimed and the preferred form of construction by which these objects are attained is shown in the accompanying drawings in which—

Fig. 1 is an end view of a tumbling mill embodying my invention partly in section to show the construction.

Fig. 2 is a longitudinal section therethrough taken on line A—A of Fig. 1.

Fig. 3 is a section taken on line B—B of Fig. 2.

The device is supported in a pair of bearing members 1 and 2 shown in Fig. 2 in which a bushing 3 is provided within which the members 4 are rotatably mounted. Each member 4 is provided with an annular flange 5 and secured to the annular flange 5 by bolts 6 is a drumhead 7 which is in disc form. Secured to the outer periphery of the drumhead 7 is the cylindrical

body 8 of the tumbling drum which is provided with a removable cover 9 shown in Figs. 1, 2 and 3 which is normally held in place by the bolts 10. This removable lid 9 is provided with a pair of handles 11 by which the lid may be removed after the bolts 10 have been removed. Rotatably mounted on the inner end of each member 4 is a ring 12 which is provided with eight flat faces arranged to receive the eight flat plates 13 as will be understood from Figs. 1 and 2. Each flat plate 13 is provided with strengthening ribs 14 and a segmental flange 15 shown in Figs. 1 and 2 is provided at each end of each plate 13 and is secured in place by the bolts 16 shown in Figs. 1 and 3 which extend through the respective plate and secure the plates to the members 12. These flanges 15 are curved at the edge so as to form a complete circle when assembled together as shown in Fig. 3 and a guard member 17 is provided which is secured to the drumhead 7 and engages over and provides a cover for the flanges 15 at each end of the device.

In order to lock the member 12 and flat plates 13 to the drumhead, a locking bar 18 is provided at each end of the device as shown in Fig. 2, which carries a bolt 19 extending through an aperture 20 provided in each drumhead and the lower end of this locking bar is adapted to engage in a notch 21 provided therefor in the member 12. There are eight of these notches 21 provided in the eight flat faces of the member 12 so that the drum may be locked to rotate with the castings in any one of eight positions. When these locking bars are moved to the position shown in Fig. 2, the drum is locked to the member 12 and plates 13 and when the locking bars 18 are raised to the upper ends of the slots 20, the members 12 and plates 13 may be rotated in relation to the drum or the drum may be rotated in relation to the said members.

In order to drive the drum, a large gear 22 is secured to the end thereof by the bolts 23 shown in Fig. 2 or in any other suitable manner and this gear may be provided with a spider having a series of four or five spokes so secured to the drumhead. The gear 22 being secured to the drumhead provides a means for driving the tumbling mill by means of a pinion meshing with the said gear 22 (though not here shown).

On the outside, each plate 13 is provided with a series of transverse ribs 24 shown more particularly in Fig. 1 and adjacent each rib is an opening 25 through which a hook 26 extends. Each plate 13 on the underside is provided with a series of bosses 27 on each of which a bell

crank lever 23 is pivotally mounted. Each hook 26 is pivotally mounted on its bell crank lever 23 and to the lower or depending end of the bell crank lever one end of a stiff spring 29 is secured.

The opposite end of each spring 29 is connected to a longitudinal rod 30 which extends through the center of the mill and one rod is provided beneath each plate 13. To the end of each rod 30, a lever 31 is pivotally connected which in turn is pivotally mounted at 32 between bosses 33 provided on the end plate 34 which is rotatable on the member 4 as will be understood from the left end of Fig. 2. When the respective lever 31 is pulled outwardly as shown in the lower half of Fig. 2, the bell cranks 28 are all turned on their pivots to raise the hooks 26 as shown. While in this position, castings such as cylinder blocks 35 shown in Fig. 2 are positioned on the transverse ribs 24 of the plates 13 and the hooks 26 are engaged over adjacent portions of the castings, the hooks being designed for the particular type of casting with which the tumbling mill is used. After the hooks have been engaged over the cylinder walls as shown, the lever 31 may be turned to the position shown in the upper half of Fig. 2 and a hook 36 may be engaged thereover to hold it in place. This movement of the lever 31 draws the bar or rod 30 longitudinally to the left of Fig. 2 thus turning the bell cranks 28 by means of the springs 29 so that the hooks 26 are drawn into tight engagement with the cylinder walls to hold the same tightly against the ribs 24 on the plates 13.

This tumbling mill is for use in cleaning rough castings as hereinbefore described and the mill is preferably filled with a large quantity of tumbling jacks. After the tumbling jacks have been thrown into the mill, the mill is rotated by means of the gear 22 so that the jacks fall over and pass between and through the castings to clean the same and in this connection it will be noted that the shields 17 prevent the jacks from wearing off the heads of the bolts 6, 16 and 23.

When rotation has been continued to complete the cleaning operation, the lid 9 may be removed and the mill may be slowly turned over to discharge the jacks and foreign matter from the mill. When all loose jacks and foreign matter have been discharged from the mill, the mill may be turned so that the opening is at the top at which time, the lever 31 may be turned to release the hooks 26 for the row of castings appearing through the opening in the drum at which time, the castings may be removed one at a time and replaced by a new casting to be cleaned whereupon the hooks may be engaged over the new castings and the lever 31 turned to place a pressure on the hooks and secure the castings in place. At this time the locking bars 18 may be moved outwardly to disengage the same from the notches 21 and the bearing members 12 to free the drum from the casting supports. By means of a bar engaged in the next row of castings, the next row may be then turned to position beneath the opening in the drum and by releasing the lever 31 the next row of castings may be removed and replaced by other castings to be cleaned. In this manner, the mill may be unloaded and loaded at the same time and when completely loaded the jacks may be thrown into the drum and the lid replaced at which time, the mill is ready for the next operation. In unloading the mill if any casting

is found to need further cleaning, it may be left in place and re-secured with the other castings in its row by turning the lever 31 to place a pressure on the hooks 26. One of the features of the device is that each plate 13 as a unit with its hooks, bell cranks, springs and rods 30, may be removed for repairs by taking out the bolts 16 at each end and disconnecting the lever 31 from its pull rod 30 at which time, the entire unit may be removed through the opening in the drum for repair or replacement.

If desired, a suction blower may be connected to the member 4 at the right end of Fig. 2 to draw air through the center of the mill and to remove all dust and sand particles passing into the compartment for the rods 30. It will be noted that the rods 30 are not at any point positively connected to the bell cranks 28 but the connection is entirely through means of springs 29 which are connected to the rods 30 so that a tension is put on the leverage to cause the hooks 26 to firmly hold the castings in position.

In the present types of tumbling mills, castings, such as cylinder blocks, are positioned loosely in the mill and during rotation of the mill become wedged in place, preventing the desired movement of the jacks in cleaning and requiring considerable time in dislodging the key cylinder before unloading the mill. With this method also, the breakage of the castings by using force to dislodge the castings and by the castings bumping against each other causes considerable loss. With my device the castings are supported in fixed position to allow free movement of the jacks at all times and when unloading, any casting not properly cleaned may be left in position for the next operation of the mill. By providing spring means for actuating the hooks, a variation of thickness of the castings may be allowed and at the same time, the castings will be firmly held in position. With my device any number of castings up to twenty-four may be cleaned in the mill as it is not necessary to put in a full load of castings as is necessary with present types of tumbling mills.

From the foregoing description, it becomes evident that the device is very simple and efficient in operation, will not easily get out of order, is composed of few parts and is of consequent low manufacturing cost and provides a device which accomplishes the objects described.

Having thus fully described my invention, its utility and mode of operation, what I claim and desire to secure by Letters Patent of the United States is—

1. In a tumbling mill, a drum, means for rotating the drum, a series of members mounted within the drum and normally rotatable therewith, each member being arranged to receive a series of castings thereon, a series of hooks extending through each member and arranged to engage the castings, a bell crank for each hook pivotally mounted on the respective member and turnable to put a tension on the respective hook, yieldable means connected to each bell crank and a rod for each member connected to the bell cranks thereon and adapted to be longitudinally moved to place a tension on the bell cranks and hooks.

2. In a tumbling mill, a drum, a member mounted within the drum and normally rotatable therewith and arranged to receive a series of castings thereon, a series of hook members for engaging the castings, a lever for placing a pressure on each hook member and a series of

springs connected to the said levers and arranged to be placed under tension from the exterior of the drum.

3. In a tumbling mill, a drum, means for rotating the drum, a member within the drum and normally secured to rotate with the drum, the

said member being arranged to receive a series of castings, a hook for each casting, a bell crank for placing a tension on each hook and spring operated means for placing a tension on the bell cranks.

EDWARD W. BENSON.
